CLAIM

The ornamental design for a coin capsule, as shown and described.

DESCRIPTION

FIG. 1 is a top, front perspective view of a first embodiment of a coin capsule showing my new design;

FIG. 2 is a top view thereof;

FIG. 3 is a front view thereof, the rear view, left side view, and right side view being identical;

FIG. 4 is a bottom view thereof;

FIG. 5 is a cross-sectional view taken vertically along line 5-5 of FIG. 4;

FIG. 6 is a top, front perspective view of a second embodiment of a coin capsule showing my new design;

FIG. 7 is a top view thereof;

FIG. 8 is a front view thereof, the rear view, left side view, and right side view being identical; and,

FIG. 9 is a bottom view thereof.

The broken line showing of additional retaining elements in FIGS. 1, 2, 4, 5, 6, 7, and 9 are for the purpose of illustrating environmental structure and form no part of the claimed design.
